UNITED STATES PATENT OFFICE.

ALBION L. F. MITCHELL, OF LYNN, MASSACHUSETTS, ASSIGNOR TO THE
MITCHELL HEEL AND EDGE BURNISHING COMPANY, OF KITTERY, ME.

JACK FOR BOOTS OR SHOES.

SPECIFICATION forming part of Letters Patent No. 310,532, dated January 6, 1885.

Application filed October 23, 1884. (No model.)

To all whom it may concern:

Be it known that I, ALBION L. F. MITCHELL, of Lynn, in the county of Essex and State of Massachusetts, have invented certain Improvements in Jacks, of which the following is a specification.

This invention has for its object to provide a jack adapted to rotate a boot or shoe held by it while the heel of said boot or shoe is presented to a burnishing-tool, the boot or shoe being rotated first in one direction and then in the other, so that the surface of the heel may be repeatedly presented to the tool.

The invention consists in the several improvements hereinafter described and claimed.

Of the accompanying drawings, forming a part of this specification, Figure 1 represents a front elevation of a jack embodying my invention applied to a burnishing-machine. Fig. 2 represents an end elevation of the same. Fig. 3 represents a section on line xx , Fig. 1. Fig. 4 represents a section of a portion of the jack.

The same letters of reference indicate the same parts in all the figures.

In the drawings, a represents the standard which supports the arbor of a rotary burnishing-wheel, b , formed to burnish a boot or shoe heel.

To the standard a is rigidly attached a stout arm, c , and to the other end of this arm is connected, by a pivot-bolt, d , a yoke or bearing, e , adapted to oscillate freely on the pivot d . An arbor, f , is journaled in the yoke or bearing e , and on said arbor is mounted the supporting-frame g of the jack, said frame having bearings h , through which the arbor passes. The frame can therefore oscillate in two directions—viz., with the yoke e and arbor f on the pivot d , and independently of said yoke on the arbor f at right angles to the direction in which it is capable of oscillating on said point.

The parts of the jack that hold the boot or shoe are, first, an arbor, i , journaled in a bearing, j , in the upper end of the frame g , and provided at its upper end with a clamping-plate, k , which bears on the inner sole and has points to prevent it from slipping; and, secondly, a rod, l , mounted in a sleeve, n , affixed to a yoke or offset-bar, o , which is se-

cured to the arbor i by a set-screw, s , said set-screw also securing to the arbor i a sleeve, j' , having a pinion, h' , whereby an oscillating or rocking motion is communicated to the arbor i , arm o , and rod l , as hereinafter described. The rod l has a plate, p , at its inner end, which bears against the top lift of the heel, and is pressed against the heel by a spring, q , (see Fig. 4,) the heel being thus clamped between the plates k p . A lever, r , pivoted at s to the offset-bar o , enters a notch in the rod l , so that when the lever is turned in the direction indicated by the arrow in Fig. 1 it will force the rod l back and release the heel. The lever r is provided with a spring dog or catch, which engages with a notched segment, t , affixed to the bar o , and holds the lever at any point to which it may be moved along said segment.

The parts described are so located with reference to the burnishing-wheel b that the heel held between the plates may bear against said wheel. The oscillations of the frame g on the arbor f enable the heel to move toward and from the burnishing-wheel, and enable the frame g to move as required when the heel is rotating and is in contact with the wheel. The oscillations of the frame g and yoke or bearing e on the pivot d enable the heel to be moved across the perimeter of the wheel, so that all portions of the heel-edge may be presented to the burnishing portion of the wheel.

u represents a curved guide-rod supported by lugs v , attached to the standard a , said rod being curved, so that it is in the arc of a circle having its center in the center of the arbor f . A socket, w , is fitted to slide on the guide-rod u , said socket receiving a curved rod, a' , which is secured adjustably by a set-screw, b' , to a socketed boss, c' , on the frame g . The rod u and socket w are curved, the rod being the arc of a circle having its center in the pivot d . A spring, e' , interposed between the boss c' and socket w , serves as a buffer to prevent the boss from striking the socket when the frame g swings toward the standard a .

It will be seen that the socket w and curved rod a' constitute a telescopic connection between the frame g and standard a , said connection sliding on the curved guide-rod u .

A spring, f' , secured at one end to the sliding socket w and at the other end to the standard a , pulls the frame normally in the direction indicated by the arrow in Fig. 2, and thus 5 presses the heel against the burnishing-wheel. The arbor i is secured by a set-screw, s^2 , to a sleeve, j^2 , as above described. Said sleeve is provided with a pinion, h' , with which meshes a rack-segment, i' , on the upper end of the lever j' . Said lever is pivoted at h' to the frame g , and is provided at its lower end with a slot, l' , which receives a wrist-pin, m' , set eccentrically in a disk, n' , on the arbor f . The arbor is rotated by a belt, o' , running 15 from the driving-shaft p' , and its rotation causes the eccentric wrist-pin m' to oscillate the lever f , and thus rotate or rock the arbor i , with the boot or shoe, first in one direction and then in the opposite direction. The heel 20 is thus repeatedly presented to the burnishing-wheel, the rotations or oscillations of the arbor being sufficient to present all parts of the heel-edge to the wheel. The lever is allowed to remain nearly at rest at the end of 25 each movement, while the wrist-pin is moving nearly in line with the slot l' , the heel then remaining at rest, so that the sides of the heel, or the portions adjacent to the breast thereof, which are then in contact with the wheel, receive 30 a longer continuous burnishing action than the other parts of the heel-edge. Better results are thus produced than would be the case if all parts of the heel received the same amount of burnishing.

35 It will be observed that the jack is capable of being easily controlled by the operator, who is enabled to present any desired part of the heel-edge to the burnishing-wheel, and secure the required burnishing action without 40 hard or fatiguing exertion.

I claim—

45 1. In a heel-burnishing machine, the combination of a supporting-standard, a burnishing-tool mounted thereon, a frame pivoted to said standard to swing universally, as described, an arbor, i , and co-operating heel-clamping devices, substantially as described, mounted on the swinging end of said frame, and mechanism, substantially as described, 50 whereby said arbor and co-operating devices are oscillated, as set forth.

2. The jack composed of the yoke or bearing e , pivoted to a fixed support to swing in a given plane, the frame g , pivoted to the yoke

55 to swing in a plane at right angles to that in which the yoke swings, an arbor, i , and co-operating heel-clamping devices, substantially as described, mounted on the swinging end of said frame, and mechanism, substantially as described, whereby said arbor and co-operating devices are oscillated, as set forth.

3. The combination of the yoke or bearing pivoted to a fixed support, the arbor journaled in said bearing and provided with the eccentric wrist-pin, the frame mounted on said 65 arbor, the arbor i , journaled in the upper end of said frame, and provided with a pinion and devices, substantially as described, co-operating with said arbor to hold a heel, and the lever pivoted to the frame and provided at 70 one end with a rack-segment engaged with the pinion, and at the other end with a slot receiving the eccentric wrist-pin, as set forth.

4. The combination of the standard, having the curved guide-rod, and the jack pivoted to 75 swing in two directions, as described, and provided with the telescopic connection mounted on said curved guide-rod, as set forth.

5. The combination of the jack pivoted to swing in two directions, as described, the 80 standard having the curved guide-rod, the socket w , mounted to slide on said rod, the curved rod a' , attached to the jack, and the spring c' , interposed between the jack and the 85 sliding socket, as set forth.

6. The combination of the standard having the burnishing-tool and the curved guide-rod, the jack pivoted to swing in two directions, as described, the telescopic connection mounted to slide on the guide-rod, and the spring f' , 90 whereby the jack is pulled toward the burnishing-tool, as set forth.

7. In a jack, the combination of the arbor i , having a clamping-plate, the offset-bar o , secured to said arbor, the rod l , mounted in said 95 arm and provided with a clamping-plate, and with a spring whereby it is forced against the heel, and retracting-lever r , pivoted to the offset-bar and provided with holding devices, substantially as described.

In testimony whereof I have signed my name to this specification, in the presence of two subscribing witnesses, this 16th day of October, 1884.

ALBION L. F. MITCHELL.
